UNITED STATES PATENT OFFICE

1,982,991

FULL-FASHIONED KNITTING MACHINE

Kenneth Howie and Charles C. Krieble, Norristown, Pa., assignors to Wildman Mfg. Co., Norristown, Pa., a corporation of Pennsylvania

Application February 4, 1932, Serial No. 590,942

110 Claims. (Cl. 66—82)

The invention concerns full fashioned hosiery knitting machines and one object is to provide a single unit machine capable of making a full fashioned stocking section having all the characteristics of those made on the well known form of multiple head machines, say twenty-four stocking sections at one time. In this multiple head machine the knitting operations at each head are carried on simultaneously with similar 10 knitting operations at all the other heads, and certain instrumentalities are common to all the heads and are controlled by mechanism at the extreme ends of the machine. For instance the thread carriers for all the heads are mounted on 15 carrier rods extending and operable lengthwise of the machine from end to end so that when one of these bars is operated the thread carriers belonging to all the heads are operated simultaneously, so too, all the slur cocks are operated simultaneously as are also the sinkers and dividers 20 throughout the whole series of heads or sections. When, therefore, a broken needle at one of the sections or heads has to be replaced or other hand operation has to be performed the entire 25 machine is brought to rest and knitting at all the twenty-four sections or heads ceases. Other instances might be mentioned of the fact that when an operation by hand or an adjustment or inspection of the knitting operation at any one of 30 the twenty-four heads necessitates the stopping of the machine in order to enable the attendant to accomplish that operation, adjustment or inspection at that particular head, all the other heads of the twenty-four must remain idle. 35 Turning of the welt is a further example.

In carrying out our object of providing a single unit machine we have had in mind the production of a machine of such simple and efficient construction as will enable it to be placed on the 40 market at such a reasonable cost that a manufacturer will be enabled to start with comparatively small capital and build up his plant as his business progresses. In this connection also other objectives have been sought, namely the 45 economy of space, rapidity of operation, high production of goods, freedom from the disadvantages of temperature changes due in the long standard machines to expansion and contraction of the parts which extend virtually from end to 50 end of the machine.

With our improvement the length of the machine is kept at a minimum so that a number of machines can be placed end to end and the aggregate length of the entire number will be within 55 reasonable limits.

The invention is shown in the accompanying drawings in which

Needle bar mounting and operation

The needle bar 1, Figure 5, is mounted in brackets, one, as shown at 2, at each end thereof, there being an adjustment to each bracket consisting of a screw 3 passing through the bracket and bearing on the bar.

The brackets are pinned to a rod 4 mounted in the flexible section 5 of arms 5a which are pinned to a shaft 6 near the center of machine. The rod 4 is loosely mounted in the arm section 5. The shaft 6 is turned by a cam 7 on main cam shaft a through an arm 8 and roller 8a. The split arm 5, 5a enables the needle bar to be adjusted up and down by a screw 10 and lock nut 11.

This mechanism raises and lowers the needle bar. For swinging the needle bar for pressing the needle beards the shaft 4 has at its central part and pinned thereto an arm 12 which depends therefrom and has an adjusting screw 13 bearing on the base part of a yoke formation 14 at top of an arm 15, the lower end of which is connected by a link 16 with a web 17 of a lever 18 pivoted loosely on said center shaft 6. This lever is operated by a cam 18x, Fig. 1, on the main cam shaft a, said lever having a roller 18y bearing on the cam all as in ordinary practice.

The link 16 has a handle and also a pin and notch connection 19, Fig. 5, with the depending lever arm 15 so that by lifting the lever to disengage arm 15 the brackets 2 can be swung by hand. A spring 20 maintains engagement between the notch and pin.

Stitch control

In the formation of the stitches the needle bar 1 is operated as usual to set the needles in a certain relation to the throats of the sinkers and dividers in order to furnish the necessary amount of yarn to produce the desired length of stitch.

This is usually accomplished by the rocker lever 21, Figs. 1 and 24, loose on the rocker shaft 22. The roller 21a of this lever is operated by the stitch cam 23 on the main cam shaft a which causes the oscillation of rocker shaft 22 and this in turn through adjustable stud 22a of lever 22b, Fig. 5, fixed on shaft 22 coming in contact with presser lever 18, operates the same together with the links 16, etc., and thus the needle bar is set in desired stitch forming relation to the throat of the sinkers and dividers. The connection from the loose lever 21 to the rocker shaft 22 is through the tail 22k of the lever, Fig. 24, coming against the straight edge 22c of the arm or bracket 22d, Figs. 24 and 25, which is pinned to the rocker shaft 22. In this action of making ordinary stitches the parts 22e, 22f and 22g, Fig. 24, do not come into play but these parts are called into play by pattern mechanism for increasing the stitch length when necessary as now will be described.

When desiring to make a temporary change of stitch length such as for a loose course, a pattern stud 22h, Figs. 24 and 31, on the pattern drum A raises the lever 22g and pulls on link 22f. This operates cam piece 22e pivoted at 22i on the arm 22d which brings the high part of said cam piece in contact with screw 22j carried by the tail 22k, the lever 21 thereby setting roller 21a further inward towards stitch cam 23 and increasing the amount of oscillation of the shaft 22 when roller 21a is operated by said stitch cam 23, thereby causing a greater amount of yarn to be fed to the needle and a longer stitch to be formed.

For adjusting the needle bar intermittently as required when reinforcing the heel, at which time the loops must be longer to take care of the addi-

tional yarn, a lever 24, Fig. 1, loose on shaft 22 and having roller 24a contacted and operated by the rocker cam 24b on the main shaft and a similar series of connections to those just described, namely, like those, 21, 22d, 22e, 22f, and 22g, are operated by a button or stud like 22h on the pattern drum A to operate the needle bar into position for making long stitches suitable to receive the reinforcing yarn. This series of connections for setting the reinforcing lever 24 are indicated in part in Fig. 1 at 24f, 24h and 24g.

10 This mechanism for adjusting the needle bar when reinforcing the heel may be substituted by mechanism shown in Figs. 38 to 42 for making a tapered heel reinforcement as will be described later.

Rendering needle bar temporarily inactive

20 The lever 8, Fig. 5 which is operated by cam 7 to raise the needle bar has an upwardly extending finger 8b provided with a pin 8c. This is to be engaged at certain times by a detent hook 8d pivotally mounted on and depending from the upper structure and controlled by a pattern cam 8e mounted on the yarn change controlling shaft 25 b. This detent hereinafter referred to has a return spring 8f at its hub Fig. 7. The detent has a spring pin 8g which bears on the cam 8e.

30 At a certain point in the operation of the machine as here organized i. e. in changing thread carriers, it is necessary to allow the machine to perform an idle stroke or strokes while the necessary instrumentalities are being automatically placed in position to effect the change. At this time it is one of the objectives of this invention, automatically to prevent the needle bar from performing its regular cycle of movement. The needle bar is therefore, held down during the 35 yarn changing operation to prevent the needles from receiving yarn and to prevent a press off. For so holding the needle bar in its low position the hook or detent 8d comes into play and engages the pin 8c of arm 8b. This occurs when the roller 8a of lever 8 is nearing the high part of cam 7 and consequently the needle bar is down 40 with needle head below sinker throat. While the needle bar is thus held down the changing of the yarns takes place automatically.

Yarn carrier mechanism

50 The tubular thread guides t are mounted one on each of the substantially endless thin steel flexible bands 26, say for instance five in number in the particular machine herein disclosed. These bands are arranged side by side and are set vertically on edge. The thread guides consist of tubes t, Figs. 33 and 33a held in place by a punched out portion or portions t2 of the band. These portions grip the guide tubes and they present inclined band portions which will enable the guides to pass each other without interference.

55 The bands are closely assembled at the front of the machine and more widely spaced apart at the back of the machine as shown in Figs. 4 and 5 and diagrammatic Fig. 35. They are guided at the ends of the machine about a series of rollers 27 and about blocks 28 adjustably fixed to the frame. These bands form substantially endless carriers for the yarn guides and they are reciprocated to cause the yarn guides to traverse the 60 needle row.

65 Adjustment of the guide blocks 28 for the bands is effected by the screws 28a Fig. 4a which pass through enlarged openings in the blocks into 70 the top plate of the machine. The heads of the

screws bear on the upper faces of the blocks and clamp them to the top plate. By loosening the screw or screws the blocks may be adjusted to make the bands properly taut to prevent vibration and then by properly setting the screws 80 the block will be held in its adjusted position.

The bands may be held down in their operative plane by the discs 27a, Fig. 43, which are mounted on the studs 27b about which the rollers turn. These discs overlie the upper edges of the bands 85 and are free to turn about the posts. An oil hole is provided at 27c.

90 Guides 29, Figs. 1 and 5, are provided at the front of machine through which the whole set of bands pass closely associated. Each of the bands on its back stretch i. e. at the back of the machine has riveted or otherwise affixed thereto a dog 34, Figs. 8, 9, 10 and 35. These dogs form the connection between the ends of the bands and practically make them endless.

95 The dogs are adapted to be engaged by driving pawls 31a, one for each band mounted in a driver member or block 31 which reciprocates at the back portion, and lengthwise, of the machine, being guided on the rails 33, Figs. 4, 5, 8, 9, 10 and 100 11, which extend from end to end of the machine frame and suitably fixed thereto. The pawls 31a are so controlled as to engage their companion dogs 34 at the proper times for operating the corresponding bands 26 with their yarn guides, the 105 selection of the proper driver pawl being accomplished by selector mechanism shortly to be described.

110 For operating the driver block or pawl carrier 31 it is fixed to the upper stretch of a band chain or other suitable form of carrier shown at 30 Figs. 5, 9 and 10. In this present instance this carrier for the driver block is in the form of a thin steel band. The driver block 31 is formed in upper and lower sections 31m and 31n, Fig. 10, held together by screws 32, Figs. 9 and 10, so that these sections clamp the carrier band 30 between them and, therefore, the driver, by the movement of the band, is made to traverse the machine lengthwise back and forth.

115 The dogs 34 are also made in sections 34a, 34b, Fig. 10, and are riveted or screwed together with the band or tape 26 between them. The driver band or carrier passes around pulleys 30a mounted near the ends of the machine and it has 120 fixed thereto the slur cock carrier 37 Fig. 5 which is guided by the T-shaped frame bar 37a. The slur cock carrier has upwardly extending standards or posts 37b on each of which there is mounted a roll 37c on a vertical axis. These rolls 125 embrace a spiral rib 38a of the rotary reciprocating draw bar 38 which effects the reciprocation of the carrier band 30.

130 It thus will be seen that the rotary reciprocating screw or draw bar 38 (which is operated as hereinafter described) reciprocates the slur cock carrier which in turn reciprocates the band 30. This band reciprocates the driver block or pawl carrier 31, the pawls of which are selected for picking up their corresponding dogs 34 and operating the corresponding yarn guide carrying band 26.

135 It will be noted that the employment of the thin steel bands 26, set up on edge, enables a close assembly of these bands at the front of the machine to be obtained so that all the carriers are disposed in the same horizontal plane and close to the needle row so that the guide tubes are all 140 in close relation to the needle row for the proper delivery of yarn thereto. These bands occupy 145 150

little space vertically, leaving the upper part of the machine unobstructed for the free flow of the yarns from the overhead appliance for guiding and controlling the yarns. Further, the flexible bands permit the employment of the driving and stopping mechanism at the rear of the machine well within the lengthwise limits of these carriers, said carriers being turned to the back of the machine at the ends of the framework to 10 connect up with the driving mechanism and to reach proper association with the stop mechanism.

It will be observed that the rotary reciprocating screw or draw bar 38 as viewed in plan view, Fig. 4, is of a length less than that of the space from side to side of the machine occupied by the endless flexible means which traverse the yarn guides along the needle row, and the vertical plane in which the axis of the screw bar lies 20 is intermediate those stretches of said endless flexible means which are adjacent the needle row and those stretches which are more remote from the needle row. As viewed in Fig. 4, the rotary reciprocating screw member 38 has its axis located in a plane between the said stretches of said members and perpendicular to the plane in which the said adjacent and remote stretches of the endless flexible members lie, and the latter plane passes through said screw member 38 which, 25 therefore, is located substantially within the circuit of the endless flexible means.

It will be observed also that as the adjacent and remote stretches of the endless flexible means are connected by the flexible curved end portions, suitably guided, the action of the driver in moving any one of the remote stretches in one direction will cause the corresponding stretch adjacent the needle row to move in a direction along said row opposite to the direction of movement of the remote stretch.

Yarn carrier stops and controlling mechanism therefor

In considering this mechanism, reference will 45 be made to the lay of the product, which is of ordinary form, as it comes from the machine and as shown in the diagram Fig. 36. This will make clear the application of the terms "right hand" and "left hand" tabs, selvages, etc., it being understood that the product comes from the machine welt first and heel tabs last. Therefore, where 50 right hand heel tab is referred to herein it will mean the tab at the upper right hand corner of the diagram, and likewise, where the left hand heel tab is referred to, it will mean the tab at the 55 upper left hand corner of this diagram.

The stop and selector mechanism for controlling yarn carriers is arranged at the back of the machine and well within the lengthwise limits of the machine and of the carriers themselves. 60 This mechanism includes two sets of what may be termed outside selvage stops which determine the length of stroke of the carriers in making the width of the stocking. The pivoted stops Rs of 65 one of these sets, (see dotted lines Figs. 4 and 7), diagram 35 and Figs. 8, 9 and 10 are for the right hand selvage and this set is located towards the left hand end of the machine while the pivoted stops Ls for the left hand selvage are arranged in a group near the right hand end of the machine. Each of these sets of stops is carried by one of the brackets 36 and each bracket is adjustable 70 lengthwise of machine for narrowing, by the screw shaft 43. Each bracket is guided by the frame rod 39 and by a frame bar 38x. The stops of

these two sets face towards each other or inwardly towards the lengthwise center of the machine. There are also two sets of stops arranged at a fixed point near the lengthwise center of the rear part of the machine. Two of these stops Rt of 80 the left hand group, Figs. 4 and 35 are for determining the inner margin of the right hand reinforcement above the heel and also for determining the inside selvage of the right hand heel tab and two of the stops Lt of the right hand set 85 of these central groups determine the margin of the reinforcement and the inside selvage of the left hand heel tab, Fig. 36. All of these stops face outwardly towards their respective ends of the machine.

This central fixed group of stops also includes two pivoted hook-shaped stops Ra, one on each side of the lengthwise center of the machine for the yarn carrier #1 and these stops determine the selvage edge of the ravel courses marked ra in 90 Fig. 36.

Each group of stops Rs, Ls, Rt and Lt, the latter two groups including the ravel selvage stops Ra, has associated therewith a lever 36e which determines the up (inactive) and down (active) positions of the various stops which require to be in and out of operative position. Some of the stops do not need to be moved from operative position during the formation of the stocking. This is true of the stops in the central group for yarn 105 carriers #2, #3 and #4. These carriers never have to pass their stops of the central group Rt, Lt. Hence these stops #2, #3 and #4 remain down at all times. Because the carriers #2 and #4 have their "home" positions at the right hand 110 end of the machine, the carrier stops at right of Figure 35 controlling these carriers, #2 and #4, are either up or down according to the position of lever 36e at this end of the machine. Because the carriers #1, #3 and #5 have their "home" position at the left hand end of the machine, carrier stops controlling #1, #3 and #5 carriers are not affected by 36e at this (right) end of machine as their particular plungers 36d through which lever 36e transmits its movements to carrier stops 120 are omitted on this end, hence leaving #1, #3 and #5 always down.

At the left hand end of Figure 35, carrier stops controlling length of stroke of carriers #1, #3 and #5 are either up or down, according to the position of lever 36e at this end of machine because their home position is at this left end of the machine. Carrier stops controlling #2 and #4 carriers are not affected by lever 36e at this end of machine as their particular plungers 36d through 130 which lever 36e transmits its movement to carrier stops are omitted on this end hence leaving stops #2 and #4 always in down position, the home position for these carriers being at the right of the machine.

The reason for the above is that end stops need only to be raised to allow carrier dogs to move to their extreme or "home" position.

On left side of machine, #1 carrier in addition to being controlled by lever 36e is also controlled 140 by 36w as described at another point herein.

As above stated, the central groups of stops are arranged at a fixed point. That is the bracket 36x Figs. 4 and 7, supporting this group is fixed to the frame, for instance to the bar 39 and is 145 not subject to the action of the screw 43 because these stops do not take part in the narrowing.

Yarn carrier driving mechanism

Each yarn carrier dog 34 has an upwardly pro- 150

jecting stud 35 to abut against its appropriate one of the overhead pivoted stops of the groups above mentioned, whereby the movement of the yarn carrier dog in the direction towards said stop is arrested to stop the movement of the corresponding yarn carrier in relation to the needles.

Each yarn carrier dog 34 has a double inclined lower surface 34c Fig. 9 terminating in short inclined shoulders 34d of 45°. These dogs are engaged by their respective yarn carrier driver pawls 31a which are mounted in the reciprocating driver 31 and are guided to move vertically in said driver. There is one of these driver pawls 31a for each yarn carrier, Fig. 11, and in the present instance there are five yarn carriers #1, #2, #3, #4 and #5, Fig. 35. In Fig. 37 there are seven.

Each driver pawl has at its front and rear corners inclines 31b which form friction driving shoulders corresponding to the 45° angle of the corresponding end shoulders of the yarn carrier dog 34.

Certain selector mechanism elevates the driver pawls 31a in prescribed order to engage and drive the appropriate dogs, as will be described later.

When the driver 31 brings its selected and elevated pawl 31a against the appropriate yarn guide dog it moves the latter together with the yarn guide carrier lengthwise of the machine and the yarn delivery finger along the needle row to feed the needles. For determining the length of the stroke of the carrier the projection 35 of the dog will strike the appropriate one of the overhead pivoted stops and the yarn guide carrier will be arrested while the driver with its pawl 31a will pass on to the end of its stroke. In performing this action the active pawl 31a will yield downwardly by reason of the incline of the frictionally engaging shoulders 31b and 34d on the pawl and dog respectively and will pass beneath the arrested dog and the driver will complete its stroke.

The depressing of the pawl 31a of the driver will take place against the resistance of spring pressed restraining dogs 31c normally engaging notches 31d in the stem of the pawl, Fig. 9.

The underside of the dog 34 as stated above is inclined at 34c so that the pawl 31a of the driver will be given a slight excess movement downwardly when it is being released from the dog 34. Therefore, the driving pawl will be positioned with the straight side portion of its stem above notches 31d, opposite the ends of the dogs 31c to insure the maintenance of the release of the driving pawl from dog 34. In other words, the inclined ends of the dogs 31c will be rendered ineffective to accidentally restore the driving pawl 31a to its uppermost position.

When the driver pawl is subject to the camming action of the incline on dog 34 tending to force it down it will be free to respond to this action because its lower wedge shaped end 31g overlies the proper one of a pair of spaces or notches 31h in the driver pawl restoring cam slide 31j. The pawl remains down until this slide 31j is operated by coming against an abutment, presently described, at the end of the stroke of the driver 31. If the abutment is present at the end of the stroke (certain selector means controlling this) the restoring slide 31j for the driver pawl is operated and the incline of the projection 31g between the notches working against the lower end of the stem of the pawl 31a will raise said pawl so that it will pick up the yarn guide dog on

the return stroke of said driver and thus move this particular dog and the yarn guide band to which it is attached together with the yarn guide carried by the band so that the latter will traverse the needle row. For instance the main yarn guide would be operated in this way for making the major part of the leg of the stocking.

There being in this particular machine five yarns, though the invention is not limited in this respect, there are five yarn carrier bands, five dogs 34 and five driver pawls 31a, each of the latter having a controlling or restoring slide 31j.

The restoring cam slides 31j are restrained in their movements by coil springs 31k bearing against their sides as in Fig. 10.

80

85

90

Yarn selector mechanism

There are, as stated in the present embodiment of the invention, five yarn carriers; of which carrier #1 is for cotton to make the welt and the ravel courses; #5 is for the silk yarn for the body and in conjunction with cotton yarn of carrier #3 forms the plated area above the right hand heel tab and the right hand heel tab itself, and in conjunction with cotton yarn of carrier #2 forms the reinforced area above the left hand heel tab. Carrier #4, silk, in connection with the cotton carrier #2, forms the reinforced left hand heel tab.

95

100

Entering into the selection of these yarns are the driver pawls 31a, the pawl restoring slides 31j, and means for controlling them, as now will be referred to. This means includes selector abutments arranged in groups, one group at each end of the stroke. Some of these abutments are arranged on slideable selector plates as, for instance, C1, C3, C5, and C2, C4, Figs. 9, 12 to 16 to be adjusted into and out of line with the restoring slides 31j of the driver. At the left end of the machine there are three of these abutment carrying slides or selector plates as just noted, and at the right end of the machine there are two of these abutment carrying or selector plates or slides C2 and C4. These plates C1, C3, and C5, and C2 and C4 are adjusted by cam groups 40 and 40a, respectively, mounted on the yarn change cam shaft b, springs 42 holding the slides against their respective cams.

110

115

120

In these groups of abutments for the pawl restoring slides 31j there are also fixed abutments. At the left end of the machine there are two fixed abutments F2, F4 to cooperate with the two adjustable or selective abutments at the right end of the machine and at said right end of the machine there are three fixed abutments F1, F3, F5 to cooperate with the three adjustable selective abutments at the left end.

125

130

135

In making the portion of the leg of full width the welt is the first portion to be knitted with a cotton yarn carrier #1 being used for this purpose.

The length of stroke of the cotton yarn carrier for making welt is determined by one of the outside selvage stops Rs and Ls respectively at opposite ends of the machine against which the projection 35 of the dog 34 strikes. Suppose a rightward stroke is taking place; the appropriate stop Ls will be contacted by dog projection 35, and, as a result of this contact, the appropriate one of the pawls 31a of the driver 31 belonging to this carrier will be depressed as above described by the incline on the dog, and the driver will pass the arrested dog and proceed towards the end of its stroke. As the driver is about completing this stroke, the appropriate one of the 140

145

150

pawl restoring slides 31 $\frac{1}{2}$ will come against that one of the fixed selector abutments marked F1, Fig. 14, at the right hand end of the machine which will arrest said restoring slide so that in 5 the slight further movement of the driver the stem of the depressed pawl will ride up the inclined side of the central cam tooth 31x of said slide 31 $\frac{1}{2}$ and thus will be restored to its uppermost position to pick up the dog 34 of the cotton 10 yarn carrier #1 on its stroke to the other end of the machine. On this stroke (say to the left) the projection 35 of the dog 34 will come against the outside selvage stop Rs at the left end of the machine and substantially the same actions just 15 described will take place. In the downward movement of the pawl 31a the lower end of its stem will locate itself to the right of the upwardly tapered camming tooth 31x of the pawl restoring slide owing to the fact that when the 20 right hand stroke was being completed the pawl restoring slide, relatively speaking, shifted leftward and brought its tapered projection to the left of the vertical axis of the pawl stem. The pawl, having been lowered on the leftward stroke, 25 and left the dog 34 against the left outside selvage stop Rs, the driver passes on to the end of its leftward stroke and in the final part of this movement the pawl restoring slide strikes against the adjustable selector abutment C#1, Fig. 12, 30 and the pawl will now be restored to its upper working position by its stem riding up the incline at the right of the tapered camming tooth 31x, so that the pawl on the next rightward stroke will be in position to pick up the yarn carrier 35 dog which it had left at the left hand outside selvage stop Rs and impell it to the right. These actions go on throughout the formation of the welt, the driver dropping the dog 34 of the carrier #1 first against the selvage stop Ls at one 40 end of the machine, and then against the selvage stop Rs at the other end of the machine.

Now when the cotton welt is completed and it is desired to knit the leg of the stocking, the 45 yarn is changed from cotton to silk. This requires that the cotton yarn carrier #1 be put out of action and the silk yarn carrier #5 be brought into action. In performing this change the cotton yarn carrier must be left in its "home" position or position of rest near the end of the leftward stroke of the driver and beyond the location 50 of the left hand selvage stop Rs. For this purpose the "home" stops are provided near the end of the stroke of the driver. These "home" stops may consist of plates H fixed to the frame and 55 having notches for receiving the projections 35 of the dogs 34, the walls h at the bottoms of these notches constituting the said "home" stops.

In order that the yarn carrier dog may reach 60 its "home" stop the corresponding outside selvage stop Rs first must have been raised and held in this raised position to allow the dog 34 to pass it. This is done by the stud or cam b20 on the yarn change shaft b which operates the lever 36e, Fig. 17, to depress the plungers 36d and thus raise the pivoted selvage stops Rs, 65 Fig. 9. For convenience the lever 36e operates all the stops of its group though the lifting of only the stop belonging to carrier #1 is needed at the moment.

The dog of this cotton yarn carrier #1 after 70 passing the selvage stop is arrested by its "home" stop h. The driver 31 continues its stroke, its cotton yarn pawl releasing said dog to remain 75 against the home stop because said pawl in pass-

ing the arrested dog is cammed down by the inclined surfaces 34d, 34c of the dog.

Before the driver reaches the end of this stroke, the selector slide plate C1 will have been so controlled by the appropriate cam Ca1 Fig. 16a of cam group 40 on the yarn change shaft and the spring 42 that the selector abutment C#1 on this sliding selector plate will have been moved to a position out of line with the pawl restoring slide and hence the latter will not be arrested by this selector abutment C#1 and cam tooth 31x of restoring slide 31 $\frac{1}{2}$ will not furnish a temporarily fixed surface up which the pawl stem will rise to set the driving pawl in position to pick up this particular one of the dogs on its return, but, on the contrary, the restoring slide will maintain its position relative to the pawl stem and the pawl will remain down and on the stroke of the driver in the opposite direction, i. e., to the right, the lower pawl will pass freely under the dog 34 and leave it with the carrier #1 in its "home" position against stop h.

This particular pawl will remain down during subsequent strokes of the driver throughout the knitting of the stocking section until the ravel area is to be knit when it again will be brought into action.

At times the machine will perform an idle stroke.

(1) When placing a carrier or carriers in 105 action, having its or their "home" position on opposite side of machine from that of the carrier to be removed.

(2) Placing in and removing a carrier from action, as #1 when used for making ravel courses, 110 110 to prevent yarn from becoming engaged with needles beyond the ravel area.

In the machine described the idle stroke is first used upon the introduction of the reinforced areas above heel tab, again when the ravel yarn 115 is brought into or removed from action.

For bringing yarn carrier #5 into use the selector slide C5, Figs. 12 and 13, at the "home" station for this carrier, which is at the same end of the machine as the "home" station for the carrier #1, is operated by its cam Ca5 of cam group 40 on yarn change cam shaft b so that its abutment C#5 will be in line with the proper one of the pawl restoring slides 31 $\frac{1}{2}$ to set this slide in position so that the stem of the appropriate pawl 31a in the final movement of the driver will ride up the right hand side of the cam tooth 31x of its slide whereupon when the driver moves on its return stroke to the right the elevated pawl will pick up the dog of the yarn carrier #5 and silk yarn now will be fed to the needles. The yarn carrier #5 now will be reciprocated by the driver, and the outside selvage stops Ls and Rs at the right and left ends of the machine, having been lowered by the appropriate cams b20 acting upon and lifting the levers 36e of which there is one for each group of outside selvage stops, the knitting of the leg will be proceeded with, it being noted that in order for a carrier dog to get from its home station into position between the groups of outside selvage stops Ls and Rs at opposite ends of the machine the said dog can pass the selvage stop nearest the home station of said dog, said selvage stop being free to be tipped upwardly by said dog as 125 it passes into position between said right and left hand selvage stops. When the part of the leg at which narrowing takes place is reached, the screw shaft 43 is operated to set the outside selvage stop carrying brackets 36 inwardly towards 130 135 140 145 150

each other so that the silk carrier #5 will have its stroke progressively reduced in length at the narrowing courses until the ankle portion is reached when the two groups of the outside selvage stops Ls and Rs will remain in their positions of nearest approach while the ankle and those portions of the heel tabs above the narrowings thereof are being knit, whereupon the said groups of outside selvage stops, one at each side of the lengthwise center of the machine will again be set gradually inwardly towards each other for narrowing the lower portions of the heel tabs.

In forming the reinforcements above the heel tabs to provide the high splice above the heel, and to form the reinforced heel tab themselves, yarn carrier stops of the group Lt and Rt are in service and the cotton yarn carriers #2 and #3 are rendered active at proper times, as well as silk carrier #4. Of these carriers, silk carrier #5, together with cotton carrier #3, as previously stated, forms the right hand reinforcement above the heel and the right hand heel tab itself, and together with cotton carrier #2, the silk carrier #5 makes the left hand reinforcement above the heel.

For convenience we will refer to the stops Rt and Lt as reinforcement stops although they are in service in making the heel tabs themselves as well as the reinforced areas above said tabs. In both instances they control reinforced areas because the tabs themselves are reinforced in like manner to the reinforced areas above the tabs.

During the making of the leg the reinforcing stop Rt for carrier #5 is turned on its pivot upwardly out of the path of the carrier dog 34 because its plunger 36d is held pressed down by the lever 36e operated by the proper one of cams b20 on the yarn change shaft b.

The knitting then will be done by carrier #5 moving back and forth between outside selvage stops Rs and Ls supplying the silk yarn, and when the reinforcement above the heel is to be made the dog of carrier #3 which does the reinforcing at the right hand area, Fig. 36, will move back and forth between outside selvage stop Rs and the stop Rt, Figs. 4 and 35, it being understood as before stated that the stop Rt for carrier #3 is always down. This is because the stop has no plunger 36d associated therewith.

On these same strokes the reinforcing yarn carrier #2, which reinforces the garment at the left thereof above the heel tab, Fig. 36, will be picked up and reciprocated between the stops Ls and Lt, it being understood that the stop Lt for carrier #2 like the stop Rt for carrier #3 is always down. The actions just described will be repeated until the reinforced areas at the sides of the fabric and the intermediate ankle portion are completed.

When the reinforced right hand heel tab is reached, Fig. 36, the dog of carrier #5 will reciprocate between its outside selvage stop Rs and its reinforcing stop Rt at the left of the center of the machine of Figs. 4 and 35 and the dog of cotton carrier #3 likewise will reciprocate between its selvage stop Rs and its reinforcing stop Rt at the left of the longitudinal center of the machine.

In forming the left hand heel tab, Fig. 36, the silk yarn carrier #4 and the cotton yarn carrier #2 are brought into action by the selector mechanism, as above described, and the strokes of these carriers are limited to the distance between

the outside selvage stops Ls and the reinforcement stops Lt at the right of the lengthwise center of the machine.

Figure 16a shows the selector cams Ca1, Ca3 and Ca5 for yarn carriers #1, #3 and #5 and selector cams Ca2 and Ca4 for yarn carriers #2 and #4.

Ravel courses

For making the ravel courses at the bottom of the leg section between the heel tabs the cotton carrier #1 is used, as above stated. For limiting the movement of this carrier for these ravel courses a pair of stop levers Ra are pivotally mounted on the central fixed bracket 36x, see Figs. 4, 7 and 20. These stops have hooked ends presenting stop shoulders r facing each other or facing the lengthwise center of the machine. These stop faces r determine the selvage edges of the ravel area ra, Fig. 36.

These stop levers Ra are controlled as to their up and down positions by the appropriate ones of the plungers 36d bearing on their tail pieces which plungers in turn are controlled through the appropriate ones of the levers 36e from the cams b20 on the yarn change shaft b.

The "home" position of the cotton carrier #1, i. e. the dog 34 thereof, as before stated, is at the left end of the machine. When the knitting of the ravel area ra is completed the ravel stops Ra are raised to inactive position out of the path of the carrier dog 34 and the said dog is moved by the driver 31 to said "home" position at the left end of the machine. In this movement the dog must pass beneath the left hand outside selvage stop Rs belonging to this carrier #1. This stop, however, unless special means are provided to prevent it, would be in its low position because the lever 36e of the left hand group of outside selvage stops Rs is up, in order that the appropriate one of these stops shall be down for determining the selvage along the outside of the left hand heel tab, it being understood that for convenience and simplicity of construction the whole group of stops Rs is controlled by the one lever 36e and as a group are either up or down. Therefore, the particular one of these stops Rs belonging to the yarn carrier #1 must be raised individually in order that the ravel yarn carrier #1 may be moved past this outside selvage stop to its "home" position. The lifting of this particular selvage stop is performed gradually during the narrowing operation by a special bell crank lever 36w pivotally mounted at 36y, Figs. 4 and 17, to part of the left hand bracket and movable therewith lengthwise of the machine as the screw shaft 43 is turned in the narrowing action. In this movement of the bracket the lower end of the special lever 36w will ride up the incline 54 on a fixed frame rod 54a at the back of the machine and hence the upper end of said special lever will be gradually lowered. This upper end bears only on that one plunger of the series of plungers 36d which cooperates with that particular stop Rs which belongs to the cotton yarn carrier #1.

When the leg narrowing is completed the lever 36w will have been operated so that it is on the high part of the said rod 54a and will remain there while the heel tabs are formed. Hence this stop Rs of carrier #1 will be in raised position when the time comes for the said carrier #1 for the cotton ravel yarn to be set in its "home" position of rest. Thus the dog 34 of said carrier can move beneath this raised stop Rs in placing this #1 carrier out of service.

It has been stated previously herein that in the particular machine disclosed, as an example of one embodiment of the invention, the movable selector abutments at one end of the machine cooperate with fixed abutments at the other end of the machine for controlling the pawl restoring slides 31j. For instance, at the "home" station for yarn carriers, #1, #3, and #5, there are three of the slideable selector plates whose abutments C#1, C#3, C#5 cooperate with three fixed abutments, F1, F3, F5, at the other end of the machine, see Figs. 12 and 14. At said other end of the machine which is the "home" station for yarn carriers #2 and #4 there are two of the slideable selector plates—C2, C4, with their abutments, and these cooperate with two fixed abutments F2, F4,—at the first mentioned end of the machine. The invention, however, is not limited to this arrangement of fixed abutments at one end cooperating with movable selector abutments at the other end of the machine, it being understood that the organization disclosed is illustrative of certain principles which may be carried out in modified forms of the selecting mechanism.

Referring to Fig. 7a, this shows the series of cams b20 which are arranged along the yarn changer shaft b. The uppermost cam of this Figure 7a is the one at the right hand side of the machine (left of Fig. 7). When it operates its particular one of the levers 36e the stops of yarn carriers #2 and #4 of group Ls will be raised at the completion of the stocking for the setting of the carriers in home position.

The second cam from the top of this Figure 7a is positioned the second one from the right hand side of the machine. It comes into action only when the hooked stop Ra, used in making the ravel course, is to be raised.

The third cam from the top of Fig. 7a is for controlling the stops, of the central group, which control the carriers #1 and #5 and this cam is located the third one from the right side of the machine.

The fourth cam from the top of Fig. 7a, and from the right hand side of the machine (left in Fig. 7) is for controlling the stops of carriers #3 and #5. It raises them at the completion of the stocking.

The fifth cam from the right hand side of the machine i. e. the lowermost cam of the set shown in Fig. 7a is at the extreme left hand end of the yarn changer shaft. It operates the lever 36e of the left hand group of stops Rs when the carrier block 36 of that group is at the extreme left hand side of the machine and it raises the stop of carrier #1 so that said stop can go to home position. All the cams b20 are fixed on the shaft b and always maintain their positions relative to each other.

It will be noted from Fig. 7 that the two levers 36e immediately adjacent the lengthwise center of the machine are always in line with their respective cams b20 but this is not true of the other two levers 36e which are associated with the groups of stops at the ends of the yarn carrier stroke, but the cams of these end levers are so positioned that said levers will align therewith at the proper time in the automatic adjustment of the end carriers 36.

The yarn change shaft b is operated by a pawl b1, Fig. 5, engaging a ratchet b2 which is fixed thereon, having twelve teeth for a 30° movement of the shaft. The pawl is pressed to the ratchet by its spring b21. The pawl is operated by bell

crank lever b3 and a cam bx on the main cam shaft a. The engagement of the pawl with the ratchet is controlled by a shield b5 turnable about the shaft b. This shield when down in the position shown in Fig. 27 allows the pawl to engage and operate the ratchet b2, but when up in the position shown in Fig. 5 it prevents the pawl from operating the ratchet.

The up and down positions of this shield are determined by cam projections such as b10 on the main pattern drum. These projections operate a lever b12 pivotally mounted on a frame rod b13, Figs. 1, 27 and 31 which operates a flexible wire rod b6, Fig. 27, extending through a tube b7, the lower and upper ends of which are fixed in brackets b16, b17, Fig. 27. The upper end of the wire rod bears against the tail b8 of the shield so as to operate it in one direction while a spring b9 operates said shield in the opposite direction.

The cam bx on the main cam shaft which operates the pawl b1 is formed with a part x of intermediate height and a part y higher than the part x.

These two portions of the cam are widely separated so that at each revolution the pawl will be given a two step forward movement, each movement being equal to $\frac{1}{4}$ of a revolution of the ratchet wheel b2. These steps take place with a definite interval between them due to the spaced apart relation of the cam rises x and y, and the yarn changer shaft of course partakes of this step by step movement. The step movements of the shaft b impart like movements to the cams b20 mounted thereon, the purpose of which is the controlling of the levers 36e which takes the carrier stops out of action or puts them in raised position when it is desired to remove the present operating yarn guides prior to the selection of a new guide or guides. Upon the first half of the movement of the pawl above mentioned, cam b20 is moved from the position shown in Fig. 17, with relation to lever 36e, to the position where the hook part of lever 36e will be on top of projection of cam b20. With lever 36e in this position, carrier stops as formerly described would be in the raised position permitting the then used carrier or carriers which are to be discarded to travel to their home position. At the same time cams C1—2—3—4—5, Figs. 16a and 16b would be placed in such position as to select the new carriers to be put in action. On the second half of the movement of pawl b1, cam b20, Fig. 17, would be rotated in direction shown by the arrow to a point which would allow hook end of lever 36e to drop into its original position but on opposite side of projection on cam b20 thereby permitting yarn guide stops to assume their operative position to control the stroke of the then operative carriers.

At the completion of a stocking the yarn changer shaft will have been turned to bring cams C1 to C5 into a certain position at which all yarn carriers will be in their "home" positions where they are inoperative. For beginning a new stocking a projection on the pattern chain B will operate lever 55d, Fig. 31, to allow pawl 55 to engage ratchet 56 and move the pattern drum A $\frac{1}{2}$ of a revolution, causing projection b10, Fig. 27, to operate lever b12 and withdraw the shield b5 to operative position and allow the pawl b1 under the action of cam bx to operate the yarn changer shaft b through the ratchet b2 with the two step action as set forth.

The pattern drum A, Figure 27, has a projection 150

of double length as shown at $b10x$ in respect to the length of the projection $b10$.

It will be remembered that the projections $b10$ placed in different rows on drum A, Figure 30, 5 perform different functions, one row controlling the idler ratchet, another the automatic stopping of machine, another the control of shield $b5$, and two for regulating length of stitch.

The reason for employing a double length projection $b10x$ is in the event it is desired to bring 10 into operation any or all of these various projections without changing the position of a lever that may then be in contact with or on another of the projections. In other words, the drum A 15 may make one or more forward movements without changing the position of a lever then in contact with its projection $b10$, by lengthening or adding to projection $b10$ as many projections $b10x$ as may be necessary.

20 During the formation of that part of the stocking when no yarn change takes place the shield $b5$ will be in its uppermost position to prevent the pawl $b1$ from engaging the ratchet $b2$, said pawl then riding back and forth idly upon the shield 25 with the yarn changer shaft b at rest. At this time the actuating lever $b12$ will be resting upon the surface of the drum A, no projections being present at this part of said drum.

20 The screw or draw bar 38 is rotatably reciprocated by a pinion 38b on its shaft, Figs. 1, 3 and 30 4, a gear 38c on a stub shaft at the outer side of the end frame of the machine, a pinion 38d on said stub shaft, a segment 38e, a grooved cam 38f operating the segment, a gear 38g on the shaft 35 of the cam and a gear 38h on main cam shaft a . The main cam shaft has thereon a large gear $a1$ driven by a wide pinion $a2$ on main drive shaft $a3$ having a hand wheel $a4$ and idle and drive pulleys $a5$, $a6$.

40 Referring more particularly to Figs. 2 and 4 the screw shaft 43 for adjusting the group of outside selvage stops Ls , Rs for narrowing is rotated by a pinion 43a with which meshes gear 43b on a rotary stub shaft 43c mounted in bearing 43x and carrying a drum 43d from which a 45 steel band 43e extends over an idle pulley 43f to a lever 43g operated by a cam 43h on the main cam shaft a . The drum carries a pawl 43k Fig. 4, engaging a ratchet on the shaft 43c.

50 The screw shaft when operated sets the stops Ls , Rs inwardly towards the center of the machine, a distance of two needles as in ordinary practice for fashioning the leg of the stocking.

The screw shaft has a detent 43m and notched 55 disc 43n, Fig. 4, at one end thereof, see also at left of Fig. 7, to hold the screw shaft against overthrow and to act as an index to indicate to the operator if the shaft is in proper position rotatively relative to the narrowing sequence.

60 The rotary shaft 43c above mentioned has a handle 43j by which it may be turned to set the mechanism back to normal position for resetting the parts after a complete stocking has been knit.

The transfer points 44 are mounted in blocks 65 44a on a screw shaft 44b, Figs. 1 and 4, operated by a pinion 44c a gear 44d on a stub shaft 44x which is provided with a spring drum 44' for a steel band 44e. This drum carries a pawl 44f which engages a ratchet 44g fixed on the stub 70 shaft. The drum is loose on the stub shaft and is returned by a spring sp within it, see Fig. 2b. This band 44e runs over an idle pulley 44h to the same lever 43g just mentioned above which is operated from the cam on the main cam shaft.

75 In this way both the transfer point carriers and

the stops for the yarn carriers are set inwardly toward the center of the machine step by step simultaneously for narrowing.

The stub shaft 44x has a hand crank 44j by which the transfer points can be returned to 80 normal position by hand. This stub shaft has a notched centering wheel 44m engaged by a detent 44n mounted on the transfer frame.

Fashioning heel tabs

85

The stub shaft 44x carries a ratchet 45 to be engaged by a pawl 46, see more particularly Figs. 1 and 2. When the fashioning arms 47 are raised to lift the transfer points the pawl 46 will engage the ratchet 45 and turn the stub shaft back one tooth which movement will be transmitted to screw shaft 44b so that in narrowing at the heel tab the transfer point carrier will be properly adjusted. In this action of narrowing the outer transfer points of each set are put out of action one by one as the net result of the advance and retrograde action of the screw shaft, the retrograde movement being a fractional turn corresponding to an outward movement of one needle space. Therefore, the line of double loops 100 does not run parallel with the outer edge of the fabric, but incline in respect to said edge. This aids the production of the curvature at the heel tabs, as in ordinary practice.

The pawl 46 is thrown into action only when 105 making the heel tab.

The pawl is pivoted at 46a Fig. 2 outside of the right hand side frame of the machine. It is slotted vertically at 46b to receive a pin 46c on an arm 46d on the end of the shaft 46e which extends across the front of the machine and having bearings in the links 46f which raise the fashioning arms, see Figs. 1 and 6.

These links are pivoted at their lower ends to arms 48 mounted on a rock shaft 49, which when 115 operated lifts the fashioning points. The shaft is operated by a cam 49x on the main cam shaft a through an arm and roller 49a, Fig. 1.

The pawl is under tension of a spring 46g tending to force it into the path of the ratchet as the 120 latter is lifted by the fashioning arms 47. The pawl is held out of engagement by the pin 46c on arm 46d engaging the slot in said pawl.

At an intermediate point on this shaft 46e there is an arm 46k extending rearwardly and 125 held down in horizontal position by a catch 46n which is pivoted to a collar 46m on the upper frame rod.

The nut or block 44a carrying the transfer points is guided by a bar 44p, Fig. 1, extending 130 across the fashioning frame. When the screw has operated the right hand nut step by step leftward and the heel tab is to be fashioned, the said nut 44a comes against the catch 46n just mentioned and releases the arm 46k whereupon the spring on the pawl will act and throw said pawl 46 into operative position and then each time the transfer points are lifted the pawl will turn the ratchet one step and turn the screw shaft one step backward so that, the shaft having been turned two steps forward by the band etc., above described, the net result will be to set the transfer points inwardly, the distance of one needle.

Shogging cam shaft for narrowing

145

The main cam shaft, as in ordinary practice, is shogged rightward for narrowing.

For shogging the main cam shaft lengthwise for narrowing, a collar 50 Figs. 1, 22, 23, 23a is 150

mounted loosely by its sleeve 50a on the shaft and bears laterally against the frame D. Directly adjacent this collar there is another collar 51 fixed on the shaft by a pin 51a. These two collars besides playing their parts in the operation of shogging the main shaft also form parts of a clutch for driving the connections leading to the screw draw bar 38 and the mechanism for operating the yarn guide carriers.

10 For this purpose the loose collar 50 has its sleeve 50a bearing in the frame of the machine, said sleeve having a reduced extension to which is keyed the gear wheel 38h heretofore mentioned which is connected to the master cam 38f for oscillating the segment 38e and giving the screw draw bar its rotary reciprocation. The two collars are interlocked for transmitting power from shaft a to gear 38h by a projection 51b on the side of the collar 51 when this engages a recess 50b in the loose collar.

The rotary collar 51 has also a projection 51c having a cam shaped surface which is adapted to work against a shogging slide 52 guided to move vertically in a frame part 52a. When this shogging slide is lifted an incline 52b on the side thereof comes into the path of the projection or cam portion 51c on the rotary collar and the result is that said collar 51 with the cam shaft a to which it is fixed is shogged to the right as in Fig. 22 against the pressure of a spring 51d arranged between a fixed abutment 51e on the end of the main cam shaft and the end of the sleeve of the loose collar. At the same time that the cam shaft is shogged the rotary collar 51 is moved away from the loose collar 50 and the interlocking projection 51b carried by the rotary collar 51 is carried out of engagement with the loose collar 50 which therefore stops rotating and hence the train of gearing and connections including the master cam 38f, segment 38e etc., for driving the screw draw bar 38 and the yarn carrier mechanism and slur cock is arrested so that the transfer of stitches for narrowing may be accomplished while the yarn guides and slur cock are at rest.

For restoring the shogging slide to normal or lowered position after the fashioning or transferring action has been performed a lug 51f on the hub of the rotary collar 51 comes against the cam shaped upper end 52x of the shogging slide 52 and presses it downwardly. This takes place at the end of one revolution of the cam shaft following its shogging to the right for narrowing. The shogging slide is normally stressed upwardly by a spring 52c. When down it is held against the pressure of this spring by a lug 52d thereon engaging a shoulder 53a on a detent 53 which is pivoted to the casing through which the shogging slide is guided.

60 The detent 53 is stressed by a spring 53' to normally make its shoulder engage the lug on the shogging slide.

For releasing the detent so that the shogging slide will move upwardly to perform the shogging operation the said detent has a projection 53y which is engaged by a shoulder 53h on a rod 53i connected with a lever 53j which is adapted to be operated by a projection on the master pattern mechanism shown generally in Figs. 31 and 32. When this lever is operated the rod is moved to push the detent 53 aside and release the shogging slide which then rises under power of its spring 53c to set its upper end in position so that in the further operation of the machine and at the prescribed periods the collar 51 will be shifted

axially as above described to shog the cam shaft for the narrowing operation to be performed, and at the same time the clutch formed by collars 50, 51 and associated parts will be released to stop the yarn carrier and slur cock.

In the final movement of the bar 53i an incline 53p thereon will ride upon an incline on a projection 53m (on the cover of the casing which guides the slide,) and thus the bar will be raised to release the detent which then assumes normal position under the action of its spring.

The shogging slide has also a projection 53n which when the slide is up will lie in a recess 50e of the loose collar 50 and act as a stop to prevent the movement of said collar and the master cam and gearing which drives the screw threaded draw bar and the needle carriers. This mechanism involving this stop holds the train of mechanism leading to the draw bar inactive during narrowing.

The dogs 34 of the yarn carriers are of different lengths. Those for the splicing yarns are shorter than those for the body yarns so that the yarn guides corresponding respectively to these long and short dogs will be displaced relative to each other along the needle row so that the yarn leading from these relatively displaced guides will go to the knitting instruments in proper relation in order that the reinforcing yarn will appear on the surface of the fabric.

Tapered high splice

In making a tapered high splice above the heel a tapered cam is used to control the rocker shaft 22 so that the needle bar will be set during different lengths of successive courses, to draw long loops to accommodate the reinforcing yarn in these courses.

This taper cam P, Fig. 40, is mounted on the shaft of the master gear wheel 38g. An advantage results from the mounting of this cam on this stub shaft, because when narrowing is taking place this master gear and cam are at rest, having been unclutched when the cam shaft was shogged for narrowing, hence the taper cam is at this time out of service and the rocker shaft will not be operated and the needle bar will be in normal position. The lever p, controlled by said taper cam, has a point p2 to engage the taper cam and when the parts are at rest this point will be opposite the space between the upper and lower sections of the cam. The lever is adjusted lengthwise of the cam to be engaged by different circumferential length portions thereof by having the lever pivoted at its upper end in a carrier p3 which carrier can be shifted in the direction of the pivotal axis of the said lever.

The lever is so shifted in one direction by a flexible push rod p4, Fig. 38, formed of a wire closely wound spirally fitting in a guide tube p5 and operating a pin p6 which bears on the end of the bracket p3. This wire is operated from a cam q, Figs. 38 and 38a at the back of the machine which is mounted on a bracket q1 and is operated by a pawl q2 and ratchet q3. The pawl is operated by the lever b3 from the cam br on the main cam shaft. The engagement of pawl q2 with the ratchet q3 is controlled by a suitable shield q9 similar to the shield b5 of Fig. 27—see dotted lines Fig. 38a—which in turn is controlled as to its relative position to the pawl and ratchet by a flexible wire q10 operated by the pattern mechanism in a manner similar to the wire b6 of Fig. 27, a separate pattern chain (not shown) being provided for this purpose if desired.

150

The tube q_{13} containing this wire is mounted in the lower end q_{11} of bracket arm q_{12} , Fig. 38. We have shown sufficient of these connections to indicate their relation to the parts they are 5 to operate, the connections themselves being similar to others already described.

The cam q operates a push block q_6 guided in the bracket q_7 and said push block has a roller q_8 bearing on the cam and as the flexible wire p_4 has its terminal pin portion engaging this push block it will be operated whenever the said block is raised by the cam. The guide tube p_5 is held in a boss secured to the bracket q_7 . The tube is curved where necessary in reaching from the central rear 15 part of the machine to the left front portion, Fig. 40, of the machine where the push rod contacts with the carrier block p_3 . The carrier p_3 is returned leftward by a spring p_7 .

Normally the operation of lever p is not transmitted to the rocker shaft because the transmitting connections ordinarily have an open lost motion joint therein as shown in Fig. 41. This joint is similar to that shown in Fig. 24 at 22k, 22e controlled by the pattern mechanism.

25 This joint in Fig. 41 includes the lever 22m loose on the shaft 22 and having an adjustable screw 22t in its tail portion 22n, which ordinarily will not strike the end of the arm 22r which is pivoted to the block 22q fixed on the shaft 22. 30 But when the link connection 22s leading from the arm 22r is operated by the pattern mechanism in a manner similar to that described in connection with link 22f of Fig. 25, the said arm 22r will be set so that its end will be struck by the 35 adjustable screw 22t and then the block 22q will be operated together with the rocker shaft 22 to which it is connected. Thus the pattern mechanism determines when the oscillation of lever p as operated by the taper cam P will be effective 40 in operating the rocker shaft 22 to set the needle bar in proper position during the reinforcing of the tapered high splice. This mechanism may be substituted for rocker arm 24, cam 24b and link 24f.

45 It will be noticed from Figs. 40, 41 and 42 that there are four sections comprising the taper cam P . These sections are arranged in pairs, one pair being at the top of the cam as in Fig. 41 and the other pair being at the lower 50 part of said cam P . We have indicated the members of the upper pair as 1st and 2nd and the members of the lower pair as 3rd and 4th, see Fig. 41. The operation of the cam is such that on one stroke of the machine the taper cam section marked 1st is effective upon the rocker lever p while one of the reinforcing areas is being traversed by the yarn carrier and the one marked 2nd is effective while the thread carrier is on the same stroke but is traversing the other area to be 55 reinforced. In other words these cam sections are effective one after the other while the carrier is traversing one after the other, the areas to be reinforced in tapered form at opposite edges of the garment and on the stroke of the carrier in one direction. On the return stroke of the carrier the 60 3rd and 4th sections of the cam come into play in succession as the yarn carrier is traversing the two areas above mentioned at opposite edges of the fabric. It will be understood 65 therefore that one pair, 1st and 2nd, are effective on one stroke and the other pair, 3rd and 4th, are effective on the return stroke. Each member of each pair is adjustable by screws or bolts p_8 passing through slots in the body plate of the 70 cam.

These adjustments will enable proper timing individually to be secured of the reinforcing actions in relation to the stroke.

In Figures 37 and 39 a larger number of yarn carriers are provided than in Figs. 1 to 35. These carriers will enable a greater range of selection of yarns for different colors or other characteristics. They are selected and operated in a manner substantially as above described.

80 In Fig. 37 home stops H_1 are shown of slightly different form from those shown at H in Fig. 35 in that the notches h_1 for receiving the projections 35 of the dogs 34 are staggered relative to each other. This allows the yarn guide tubes to be set in staggered relation on the carrier bands so as to conserve space and allow the bands to be set 85 close to each other. This form of "home" stop plate may be substituted for the form shown in Fig. 35. This Fig. 37 shows the screw shaft 43 at the extreme rear side of the machine, and this 90 relation of the parts may be substituted for that shown in the other figures as for instance Fig. 4, and this feature of substitution applies in all instances where such substitution is possible. Therefore, all features of Figs. 37 to 41 inclusive 95 can be incorporated in the form of machine shown in Figs. 1 to 36.

Automatic yarn carrier stops for tapered splicing

100 For arresting the carriers for the reinforcing yarns of the tapered area special stops S , Figs. 37, 39 and 39a are provided. These are adjusted automatically during the formation of the tapered reinforcements by the same cam q at the back of the machine as referred to above. The push 110 block q_6 operates two flexible wires similar to those previously described which pass through guide tubes s_2 to the stops mounted on the center bracket at the back of the machine. The flexible 115 wires push the stops outwardly and springs s_3 return them to normal position. These springs are supported at their ends by the brackets s_6 , Fig. 39a.

120 These stops face outwardly toward the ends of the machine. They are carried by rods s_4 , Fig. 39a, which are mounted slidably in the bracket. The push rods bear at s_5 in sockets of the stops S .

The cam q is so shaped as to give a step by step movement to the shiftable lever p and to the stops S for making the tapered high splice.

125 It will be understood that at the commencement of the formation of the tapered reinforced area above the heel the roller q_8 of the push block q_6 , Fig. 38a, will be under control of the apex portion of the cam q , and the lever p , Figs. 130 40 and 41, will consequently be alongside the narrow part of the taper cam P , also the stops S for the carrier band of the reinforcing yarn will be in their outermost positions. These positions of the lever p and stops will be due to the action 135 of the cam q on the push block q_6 whereby this block has been lifted step by step and has operated the push rods leading to the said lever p and stops S , to set the parts in position for making the tapered high splice. Now as the cam q is turned 140 step by step the push block q_6 will be lowered step by step and the lever p will move step by step towards the wider part of the taper cam P , i. e., towards the left in Fig. 40, this movement being under pressure of spring p_7 . Likewise the 145 stops S will be moved step by step under pressure of their springs s_3 to arrest the splicing yarn carrier means for making the tapered reinforcement, and these actions will continue until the low part of cam q is brought uppermost as in Fig. 150

38a and as a consequence the push block q6 will have completed its downward movement and the tapered high splice will thereby be finished.

Pattern mechanism

5 The pattern mechanism includes a pattern drum A driven by a pawl 55 and a ratchet 56, a pattern chain B operated by a sprocket wheel 57 which in turn is operated by a ratchet 58 fixed thereto by screws 59, Fig. 20 alongside of which chain ratchet there is an idle ratchet 60 held frictionally against said ratchet 58 by the friction member 61 which is under tension of springs 62 pressing the friction member with its flange 60a against the idle ratchet. The springs are held by the screws 63.

The idle ratchet is operated by a pawl 55a which has a broad end 55b to overlie both ratchets 58 and 60. The idle ratchet has an extra deep tooth 20 at 60b which allows the pawl 55b at a predetermined time to engage the chain ratchet 58 and turn the same. This idle ratchet permits the use of a shorter chain than would be necessary otherwise. This idle ratchet also has shallow teeth 60c and moderately deep teeth 60d in alternation as shown in Fig. 29.

The ratchet 56 of the drum A has shallow teeth and other teeth of intermediate depth in alternation.

30 The pattern drum is provided with a plurality of circumferential rows of holes 64 to receive pattern studs some of which are shown at b10 and the studs are positioned in the drum to operate the various levers at the proper times.

35 The pawls 55, 55a are both operated by a lever 55c which in turn is operated from a cam 55x on the main cam shaft, giving the pawls two operations for each revolution of the said cam shaft.

The chain carries at certain intervals projections for operating respectively the lever 53j, and 40 55d. The first mentioned lever 53j controls the main cam shaft shogging mechanism through the link 53i. The lever 55d when raised by one of the projections on the chain permits the pawl 55 to drop into the drum ratchet 56 for operating the drum one step forward. For this purpose the lever 55d is cam shaped as shown in Fig. 32 at 45 55e and on this cam portion a pin 55f of lever 55 rides.

50 This cam shaped lever is controlled by a cam member 66, Fig. 32, on the drum A engaging a pin 67 projecting laterally from the said lever. The cam has a notch about midway of its length.

Referring to drum A, in certain of the first 55 series of holes are placed projections b11 in line with lever 64' mounted on a pin b13. The hub of this lever 64' has a projection 65 to lie at times in the path of a pin 60c on the idle ratchet 60 when lever 64' has been raised by the stud or cam 60 piece b11 on drum A. This will arrest the idle ratchet in a definite position.

The second series of projections on the drum A counting from the top of Fig. 31, controls the lever b12 for controlling the pawl b1 for operating the yarn changer shaft b. The third row of projections on the drum is extra.

The fourth row of projections is for stopping the machine for the turning of the welt and at the end of knitting the stocking.

70 The fifth row of projections is for controlling the rocker mechanism which adjusts the needle bar for reinforcing the fabric above the heel and the reinforcement at the heel tabs, and the sixth row of projections controls the loose course stitch.

75 The pawl 55a is controlled by the slotted link

68 operated from a bell crank lever 69, Fig. 6, loosely mounted on rock shaft 69, operated in turn by a two point cam 70 on the stub shaft at the master gear.

A stop motion connection is shown at 71 in 80 Figs. 1 and 31, operable by a lever 72, Fig. 31, which in turn is operated by studs 73 in drum A. One of these is for stopping the machine at the completion of the welt and the other is effective to stop the machine at the completion of the leg. Any suitable let-off mechanism may be used, operated by the connection 71.

The slot in link 68 allows the pawl 55a freedom of movement on its return stroke in riding over the teeth of the ratchet. Referring to Fig. 40 the cam 70 shown in Figs. 1 and 6 of the stub shaft of the master gear 38g is of a different form in this Fig. 40. It consists of a pin 70x on the side of the taper cam P. This operates a lever 69x mounted on the rod 22 which lever in turn 90 operates a link 68x connected to the pawl 55a before described.

Where mechanism shown in one figure or figures of the drawings is capable of being used in other figures or is capable of being substituted 100 for mechanism shown in said other it is to be considered as though shown in or substituted for means shown in said other figures. As an instance of this, the forms shown in Figs. 37 to 42 inclusive are to be considered as embodied in the 105 form of machine first described.

Figs. 9, 10 and 11 show at 39p a passageway or channel at the top of the driver 31 for receiving the dog. This passageway presents bottom, side, and top walls which will sustain the dog, together 110 with the thin flexible flat band against deflection when said dog is receiving the driving thrust from the pawl 31a. When the dog is arrested by one of the stops the pawl recedes to its low position, the driver then can pass the arrested dog, said 115 dog relatively speaking passing freely through the passageway. When the pawl 31a is raised to operative position its upper part is slightly above the bottom of the passageway so as to strike the dog and move it along with the driver until arrested by one of the stops. The channel is open at the top for the stop.

The driving and stopping forces act upon the dog of the endless band. Therefore these forces are received by the band at substantially the 125 same point in the circuit of the band. This prevents any tendency for the band to deflect or buckle up as would be the case were the driving force applied to one point in the circuit, and the stopping action were applied at a point separated 130 at some distance from the driving pawl. By having both forces imposed upon the dog no damage to the thin band can take place.

We claim:

1. A full fashioned stocking machine having a 135 plurality of yarn guides, flexible bands set up on edge and wholly supporting and carrying said yarn guides and driving means for reciprocating said bands to make the yarn guides move along the prescribed needle row.

2. In a full fashioned stocking machine and in combination, yarn carriers consisting of flexible bands arranged adjacent the needle row, in close relation to each other, and set up on edge, and means at the rear of the machine for selectively 145 driving said bands and for stopping the same variably, substantially as described.

3. Apparatus according to claim 1 in which the flexible bands are arranged adjacent each other and in the same horizontal plane. 150

4. A full fashioned stocking machine having a plurality of yarn guides, flexible bands set up on edge carrying said yarn guides, and driving means for reciprocating said bands to make the 5 yarn guides move along the prescribed needle row, said bands being substantially endless with their forward stretches close together and their rear stretches comparatively widely separated, the driving means for said bands engaging the 10 rear stretches thereof and the yarn guides being carried by the closely set front stretches, substantially as described. 80
5. A full fashioned stocking machine having a plurality of yarn guides, substantially endless 15 flexible bands carrying said guides and set up on edge with means for guiding the same, means for engaging the rear stretches of said band for reciprocating the same, and stop means for limiting the movement of the bands in either direction, said stop means cooperating with the rear 20 stretches of the bands, substantially as described. 85
6. A full fashioned knitting machine having a plurality of yarn guides, substantially endless bands for operating said guides and arranged one 25 within the circuit of another with their yarn guide stretches close together adjacent the needle row and with their more remote stretches comparatively widely spaced apart, reciprocating driving means cooperating with the said more 30 remote stretches to reciprocate said endless bands to make the yarn guides traverse the prescribed length of needle row, said driving means having means to pick up and release the bands, and stop 35 means for arresting the bands to limit the traverse of the yarn guides in prescribed order, said stop means cooperating with the said more remote stretches of the bands substantially as described. 90
7. Apparatus according to claim 6 in which the 40 means for picking up and releasing the yarn carrier bands has frictional connection with the bands whereby when the bands are arrested by the stop means the driving means can pass on to complete the stroke. 95
8. Apparatus according to claim 6 in which the means for picking up and releasing the yarn carrier bands are yieldingly mounted in the driver and have frictional engagement with the bands whereby when the bands are arrested by the stop 45 means the driving means can pass on to complete the stroke, substantially as described. 100
9. Apparatus according to claim 6 in which the stop means for the endless bands comprise stops at opposite ends of the machine and means for 50 adjusting the stops step by step towards the center of the machine for narrowing. 105
10. Apparatus according to claim 6 in which the endless bands have dogs thereon and the reciprocating driving means has pawls to engage the said dogs, and said stop means engage said 55 dogs for arresting the bands substantially as described. 110
11. In a full fashioned knitting machine, a row of needles, a plurality of yarn guides, substantially endless bands for moving the same along the needle row, dogs on said bands, a reciprocating driver, pawls on the driver for engaging said dogs, and automatically operating selecting 60 means for the pawls to determine which of the 65 pawls on the driver will be set in position to engage and drive its corresponding dog and band, and automatically operable stop means for arresting the bands at prescribed periods, substantially as described. 115
12. In a full fashioned knitting machine, a row 70 of needles, a plurality of yarn guides, substantially endless bands for moving said guides along the needle row, dogs on the endless bands, a reciprocating driver, pawls thereon to frictionally engage the dogs, said pawls being yieldingly mounted, stops to engage the dogs on the bands to arrest the same whereupon the pawls will retract and pass the arrested dogs to permit the driver to complete its stroke, means for retaining the retracted pawls in retracted position, means for automatically selecting and advancing the pawls in prescribed order to pick up the dogs and reciprocate the yarn carrier dogs and means for automatically adjusting the stops for narrowing. 120
13. In a full fashioned knitting machine yarn guides, endless flexible carrier bands therefor set up on edge, dogs on the bands extending above and below the same, friction drive means for said carrier at the rear part of the machine engaging the under parts of the dogs, and stops for the carriers at the back of the machine, engaging the upper parts of said dogs substantially as described. 125
14. In combination in a full fashioned stocking knitting machine, a row of needles, a yarn carrier means for reciprocating said yarn carrier consisting of a screw shaft having rotary movement first in one direction and then in the other direction, and extending with its axis parallel with the needle row and a connection driven by the screw shaft for imparting reciprocations to the yarn carrier, substantially as described. 130
15. In combination in a full fashioned knitting machine, a plurality of substantially endless flexible yarn carrier bands, having stretches extending along the needle row, a screw shaft extending lengthwise of the machine, means for giving rotary reciprocating movement to said shaft, a driver for the bands driven from the screw and selecting mechanism to determine which band will be operated by the driver. 135
16. In a full fashioned knitting machine according to claim 15, means for transmitting movement from the screw shaft to the driver comprising a slur cock support and a flexible carrier operated by movement of said support, said carrier being connected to the yarn carrier driver, substantially as described. 140
17. In a full fashioned knitting machine yarn carriers, a reciprocating driver, a plurality of vertically slidable pawls one for each carrier, mounted in the driver for connecting with or disconnecting from their respective carriers, pattern controlled means for selecting and operating the said vertically slidable pawls in prescribed order to pick up and move their respective yarn carriers, said pawls having inclined shoulders to engage the carriers on either stroke and means for applying frictional restraint to said pawls to hold them in operative position and to allow said pawls to release themselves from the carriers when the latter are arrested, said pattern mechanism positively moving the pawls to operative position, substantially as described. 145
18. In a full fashioned knitting machine, yarn carriers, a reciprocating driver, yielding pawls, one for each of the carriers movably mounted on the driver, and each adapted to connect with and disconnect from the carriers on either stroke of the driver, stops arranged to arrest the carriers, and cause the pawls to release themselves from the arrested carriers, and selector means for the pawls for restoring them in prescribed order for picking up their respective carriers in prescribed order. 150

19. In a full fashioned knitting machine a plurality of yarn carriers, reciprocating driving means arranged in a plane below the carriers including a plurality of vertically yielding pawls 5 frictionally to engage with and disengage from their respective carriers from below, stops to arrest the carriers arranged above the same, and to cause the pawls to yield and release themselves from the carriers and selector means to restore the pawls to operative position, substantially as described. 80
20. In a full fashioned knitting machine a plurality of endless band yarn carriers, a block for driving the yarn carriers reciprocally mounted 15 at the rear of the machine, yielding pawls on the block to engage and disengage the rear stretches of their respective carriers, and means for restoring the pawls in prescribed order to position for engaging their respective carriers, said carriers having yarn guides on their front stretches. 85
21. In a full fashioned knitting machine, yarn carriers, means for operating the carriers, including a reciprocating driver, yielding devices 20 on the driver each for connecting with its carrier on either stroke, stops for arresting the carriers, and selecting means for rendering the devices operative, said stops being arranged at the rear of the machine and within the limits of movement of the driver and with the selector 25 means at the ends of the driver's stroke, substantially as described. 90
22. In a full fashioned knitting machine yarn carriers in the form of endless bands having yarn guides on their front stretches, a reciprocating driving means for picking up and moving the rear stretches of the carriers in prescribed order, stops for the carriers to determine the width of the body of the fabric, and the outer selvages of the heel tabs, stops for determining 30 the inner selvages of the heel tabs, home stops for the idle carriers, selector means to control the driver means in picking up the carriers in said prescribed order, said stops being arranged at the back of the machine cooperating with 35 the rear stretches of the band and with the inner selavage stops nearer the lengthwise center of the rear stretches of the carriers and with the home stops nearer the ends of the machine and with the selector means out beyond the home 40 stops and in line with the line of movement of the driving means, said driving means operating at one edge of the endless bands and the stops operating at the other edges of the endless band carriers, substantially as described. 105
23. In a full fashioned knitting machine, yarn carriers consisting of substantially endless flexible bands, closely associated at the front of the machine and widely spaced at the rear of the machine, means for guiding the bands at the ends 45 of the machine, a driver reciprocating at the back of the machine along the widely spaced portions of the carriers, pawls carried by the driver to engage and disengage the carriers, carrier stops near the lengthwise center of the machine, outside selavage stops at each side of the center stops and nearer the ends of the machine, home stops for the carriers beyond the outside selavage stops, and selector means for the pawls, all of said stops, the pawls and the selector 50 means being at the rear of the machine co-operating with the widely separated rear portions of the bands. 110
24. In combination, in a full fashioned stocking machine, yarn guides reciprocal at the front 55 of the machine, means disposed at the rear of the machine including a plurality of dogs, one for each yarn guide, reciprocal lengthwise of the machine for operating the guides, selective driver means for said dogs, stops at the rear of the machine movable up and down out of and into the path of movement of the dogs and means for raising the stops, substantially as described. 115
25. A full fashioned stocking machine according to claim 24 in which the stops are mounted in brackets supported by the frame and extending above and transversely in relation to the path of movement of the dogs, substantially as described. 120
26. A full fashioned stocking machine according to claim 24 in which the stops are pivotally mounted to allow dogs to pass them in one direction and to arrest the dogs in the opposite direction. 125
27. A full fashioned knitting machine according to claim 24 in which the means for raising the stops consist of a member having connection with a plurality of said stops to control all of them simultaneously. 130
28. In combination, in a full fashioned stocking knitting machine, yarn guides, stops adjacent the path of movement of said guides for controlling the action of said guides, said stops being arranged in two groups near the lengthwise center of the machine, and a group of outside selavage stops at each side of the center groups and nearer to the ends of the machine, means for automatically adjusting the outside selavage stops inwardly towards the lengthwise center of the machine, the centre groups including stops for the inner margins of the heel tabs and stops for the outer ends of the ravel courses, means for rendering the stops inactive in groups and means individual to that one of the outside selavage stops which lies opposite one of the ravel stops for making the said selavage stop inactive and a home stop beyond said selavage stop to receive the ravel 135 yarn carrier. 140
29. In combination, in a full fashioned stocking knitting machine, yarn guides, stops adjacent the path of movement of said guides for controlling the action of said guides, said stops being arranged in two groups near the lengthwise center of the machine, and a group of outside selavage stops at each side of the center groups and nearer to the ends of the machine, means for automatically adjusting the outside selavage stops inwardly towards the lengthwise center of the machine, the centre groups including stops for the inner margins of the heel tabs and stops for the outer ends of the ravel courses, means for rendering the stops inactive in groups and means individual to that one of the outside selavage stops which lies opposite one of the ravel stops for making the said selavage stop inactive and a home stop beyond said selavage stop to receive the ravel 145 yarn carrier, the means for rendering the groups of stops inactive comprising a shaft, cams thereon, members operated by the cams and extending to the stops, and the means individual to one of the selavage stops being operable as a result of narrowing action substantially as described. 150
30. In combination, in a full fashioned stocking knitting machine, yarn guides, stops adjacent the path of movement of said guides for controlling the action of said guides, said stops being arranged in two groups near the lengthwise center of the machine, and a group of outside selavage stops at each side of the center groups and nearer to the ends of the machine, means for automatically adjusting the outside selavage stops in-

- wardly towards the lengthwise center of the machine, the centre groups including stops for the inner margins of the heel tabs and stops for the outer ends of the ravel courses, means for rendering the stops inactive in groups and means individual to that one of the outside selvage stops which lies opposite one of the ravel stops for making the said selvage stop inactive and a home stop beyond said selvage stop to receive the ravel yarn carrier, said last means comprising means for adjusting the group of outside selvage stops for narrowing, a fixed incline and a connection leading from and operated by said incline to the said individual outside selvage stop.
31. In combination, in a full fashioned stocking knitting machine, yarn guides, stops adjacent the path of movement of said guides for controlling the action of said guides, said stops being arranged in two groups near the lengthwise center of the machine, and a group of outside selvage stops at each side of the center groups and nearer to the ends of the machine, means for automatically adjusting the outside selvage stops inwardly towards the lengthwise center of the machine, all the stops being pivotally mounted, the outside selvage stops facing inwardly and the centre stops facing outwardly, home stops arranged beyond the outside selvage stops, and means for raising the outside selvage stops and the centre stops, substantially as described.
32. In a full fashioned knitting machine, endless yarn carriers, yarn carrier stops arranged to cooperate with the rear stretches of the yarn carriers, a cam shaft extending lengthwise of the machine, cams on said shaft and means operated by said cams for determining the position of the stops, substantially as described.
33. A full fashioned machine according to claim 32 in which the means operated by the cams consist of bell crank levers reaching over the rear stretches of the yarn carriers.
34. In a full fashioned knitting machine, yarn guides, stops in rear of the line of movement of the yarn guides for determining the length of movement of said guides, means for automatically lifting said stops to inoperative position, a reciprocating driver for the yarn guides, selecting pawls in said driver, selector means for said pawls arranged at the ends of the strokes of the driver, a yarn change shaft extending lengthwise of the machine at the rear portion thereof, cams on said shaft for operating the stop lifting means, and cams on said shaft for operating the selecting means.
35. In a full fashioned knitting machine, yarn guides, dogs connected with said guides, each having reversely set inclined shoulders, stops to arrest the dogs, a driver for the dogs having yieldable pawls to engage the dogs, said pawls having friction engagement with the dogs through the reversely set inclined shoulders to release themselves from said dogs on either stroke when the dog is arrested, substantially as described.
36. A full fashioned knitting machine according to claim 35 in which the dogs have double inclines on their lower sides to give the pawls an excess movement in releasing the same and spring detents for holding the pawls in released position, substantially as described.
37. In a full fashioned knitting machine, yarn guides, dogs for operating said yarn carriers, a reciprocating driver, pawls thereon for engaging the dogs, said pawls being yieldingly mounted, restoring means for said pawls mounted on the driver and having a back and forth movement and selector means on the frame at opposite ends of the stroke of the driver operating said restoring means first in one direction and then the other for setting the pawls in position to operate the dogs.
38. In combination in a full fashioned knitting machine, a slur cock and means for operating the same comprising a rotary reciprocatory screw shaft extending lengthwise of the machine, and a slur cock carrier engaging the spiral of said screw shaft, substantially as described.
39. In combination, in a full fashioned knitting machine, means for giving movement to reciprocatory parts of said machine comprising a shaft having a spiral rib thereon, said shaft extending parallel with the needle row and means for giving rotary reciprocating movement to the shaft arranged at the end of the machine, consisting of a segmental gear and means for oscillating said gear, said shaft having a pinion at its end meshing with said segmental gear, substantially as described.
40. In combination in a full fashioned knitting machine, yarn guides, means for reciprocating said guides along the needle row having substantially parallel portions respectively adjacent and remote from the needle row and flexible curved portions at the ends of the machine with means for guiding said flexible curved end portions, a reciprocating driver, having means to pick up and release said parallel remote portions of the yarn guide reciprocating means, stops to arrest said remote portions, means for controlling said stops, to set them in and out of operative positions, home stops for said remote portions nearer the ends of the machine than the stops first mentioned, and selector mechanism for controlling the pick up means on the driver, substantially as described.
41. In combination in a full fashioned knitting machine, yarn guides, flexible carriers connected therewith, means for guiding said carriers at the opposite ends of the machine, means at the rear of the machine for selecting and driving said carriers in prescribed order and stop means at the rear of the machine to determine the limits of reciprocating movement of said yarn guides.
42. In combination in a full fashioned machine, yarn guides, flexible bands carrying said guides and having parallel portions at front and rear of the machine, means for guiding said bands, a rotary reciprocatory member having a spiral, a slur cock and reciprocatory band driver connected with said spiral to be operated thereby, means on the driver for picking up and releasing the bands in prescribed order, stops at the rear of the machine for limiting the movement of the bands, said stops including those for determining the widths of the knitted fabric at various points thereof, means for setting said stops in and out of operative position, home stops for determining the positions of the idle bands, and selector means for controlling the pick up means on the driver to pick up and release the carrier bands in prescribed order, substantially as described.
43. In a full fashioned knitting machine, a row of needles, the combination of yarn guides, reciprocal flexible members arranged in close parallel relation adjacent the needles and carrying said guides, and means for reciprocating said flexible members arranged parallel therewith and opposite thereto, substantially as described.

44. In a full fashioned knitting machine according to claim 43, inclines on the flexible members adjacent the guides the direction of inclination of said inclines being lengthwise of the band 5 whereby the guides are adapted to pass each other.
45. In a full fashioned machine according to claim 43, inclines on the flexible member consisting of struck out portions of said members 10 engaging and holding the guides and providing inclines which, together with the flexing of the said members, enable the guides to pass each other.
46. In a full fashioned machine, according to claim 43, inclined pieces attached to the flexible members at the guides the direction of inclination of said pieces being lengthwise of the band, substantially as described.
47. In a full fashioned knitting machine and 20 in combination, a main frame, a main cam shaft journaled therein, yarn carriers, a slur cock, driving connections for the yarn carriers and slur cock operated from said cam shaft, means for shogging the said cam shaft for narrowing, a 25 clutch which is released by the shogging of said shaft for disconnecting the said shaft from said connections to arrest the movement of the yarn carriers and slur cock during narrowing, said driving connections being located on the outer 30 side of the frame.
48. A full fashioned knitting machine according to claim 47 in which the connections for driving the yarn carriers and slur cock includes a gear coaxially arranged with and driven by the 35 clutch from the cam shaft, a cam, a gear mounted on a stub shaft parallel with the cam shaft driven from the gear on the cam shaft and connected with said cam for rotating the same, and means operated back and forth by said cam for imparting reciprocating movement to said yarn carriers 40 and slur cock, substantially as described.
49. A full fashioned knitting machine according to claim 47 in which the main cam shaft carries one of the clutch members fixed thereto, and 45 the other clutch member has a sleeve extending therefrom through the frame to the outside thereof, a gear on the outer end of said sleeve, a second gear mounted on the outer side of the frame and driven from the gear first mentioned, 50 a cam on the outer side of the machine and driven by said second gear, a segment oscillated by the cam and means operated by said segment for reciprocating the yarn carriers and the slur cock.
50. In a full fashioned knitting machine a 55 needle bar, a stitch cam, connections operated by the stitch cam for moving the needle bar towards and from the sinkers, including a lever operated by the cam, a rocker shaft to be operated by said lever which is mounted loosely thereon and is provided with an abutment which engages an abutment on the rocker shaft, means operated by said rocker shaft for rocking the needle bar, and means for adjusting the lever in relation to the cam and its abutment relative to the abutment 60 on the shaft comprising a pivoted cam piece, the pivot of which is fixed relative to one of said abutments, said cam piece when turned on said pivot adjusting the abutments relative to each other, said cam then forming the contact piece between said abutments, and pattern mechanism for operating said cam piece, substantially as described.
51. In a full fashioned knitting machine, yarn 65 changer mechanism, a needle bar, means for operating the needle bar up and down relative to the sinkers, a detent for holding the needle bar 70 in its low position, during yarn changes, and a cam for automatically controlling said detent to set the same in position for engaging a part of the needle bar mechanism.
52. A full fashioned knitting machine, according to claim 51 in which the detent is operated from said cam by a spring pin, substantially as described. 80
53. In combination in a full fashioned knitting machine, yarn carriers, stops for limiting the strokes of the yarn carriers, a screw shaft for adjusting the stops, transfer points, a screw shaft for adjusting the transfer points, pivoted 85 fashioning arms carrying said screw shaft, drums connected with the screw shafts, bands extending from said drums, a lever to which the bands are connected and a cam for operating the lever whereby the stops and the transfer points are adjusted simultaneously.
54. In combination in a full fashioned knitting machine, a main frame, transfer points for narrowing the fabric, fashioning arms pivotally mounted on the main frame, a screw shaft for adjusting the transfer points mounted in said arms, a pawl mounted on the main frame and 90 adapted to engage a ratchet connected with the screw shaft for giving the same a backward movement as said arms rise, links for operating the fashioning arms, a shaft mounted in the links, means on the said shaft for controlling 95 the position of said pawl and having a sliding connection therewith, means for holding the said shaft with the pawl in inoperative position, said means being released by contact of the transfer point carrier therewith when the heel 100 tab narrowings are to be formed, substantially as described.
55. A full fashioned knitting machine comprising a main frame, a fashioning frame pivotally mounted on the main frame, narrowing 105 points, a screw shaft mounted on the fashioning frame for adjusting the narrowing points, means for operating the screw shaft, a ratchet connected with said screw shaft for turning it backwardly and a pawl on the main frame for engaging the ratchet when the same rises with the fashioning frame for turning said screw shaft backwardly for heel tab narrowing, and 110 means movable with the fashioning frame and operable by the narrowing point carrier for controlling the said pawl to render the same operative when the heel narrowings are to be formed, substantially as described.
56. In combination in a full fashioned knitting machine narrowing points, a carrier block 115 therefor, a pivotally mounted frame carrying said points, means for adjusting said points for leg narrowings, a pawl and ratchet mechanism for adjusting the narrowing points backwardly 120 for heel narrowings and means operable by the point carrier block during its adjustment for rendering the pawl and ratchet mechanism effective in retracting the narrowing points, substantially as described.
57. In combination in a full fashioned knitting machine, a main cam shaft, means for shogging said shaft lengthwise for narrowing, comprising a collar fixed to said shaft, means controlled by jacquard mechanism to engage said collar and shift the same axially together 125 with the cam shaft, connections driven from the cam shaft for operating the slur cock in the knitting operation, said connections including a clutch member arranged adjacent said collar and coaxially with the cam shaft, said member 130

- and collar having interlocking engagement when the cam shaft is in position for knitting and being disengaged to stop the knitting operation when the said collar with the cam shaft is 5 shogged for narrowing.
58. A full fashioned knitting machine, according to claim 57, in which the jacquard controlled means, when in position to effect shogging of the cam shaft, acts as detaining means 10 for the clutch member and the connections operated thereby, substantially as described.
59. A full fashioned knitting machine, according to claim 57, in which said jacquard controlled means includes a slide having a camming 15 action on the said collar for shogging the shaft, and also has a detent portion to hold the clutch member and the connections driven thereby.
60. In a full fashioned knitting machine, reciprocating yarn guide carrier means, stops for 20 controlling said carriers in making tapered reinforcements and means for adjusting said stops comprising a cam, and flexible rod connections operated by said cam and extending to said stops.
61. In a full fashioned knitting machine, reciprocating yarn guide carrier means, stops for 25 controlling said carriers in making tapered reinforcements and a taper cam, a lever shiftable along said taper cam to be operated for different lengths of time thereby, a rocker shaft for controlling the position of the needle bar for varying 30 the lengths of the stitches, a connection between said shiftable lever and the rocker shaft, and means for setting the stops in different positions and for shifting the lever along the taper cam, said means comprising a cam, a push block 35 operated by the cam, connections extending from the push block to operate the stops, and flexible means extending from the push block for operating the said shiftable lever, substantially as described.
62. In a full fashioned knitting machine, yarn carrier bands having front and rear portions, a bracket extending over the rear portions of the 40 yarn carrier bands, stops mounted in said bracket and slideable in a direction lengthwise of the carrier bands, and means for adjusting said stops step by step along said bands, said bands having dogs to engage said stops, substantially as described.
63. A full fashioned knitting machine comprising 45 yarn carrier means selective driver means for operating the carriers in prescribed order, selvage stops for the carriers, dogs on the carriers to engage said stops, a bracket at the lengthwise center of the machine, groups of stops mounted 50 on said bracket, some of said stops of said groups being adjustable up and down relative to said dogs, and other stops of said groups being adjustable step by step lengthwise of the said yarn carriers.
64. In a full fashioned knitting machine, fashioning means, a cam shaft, means for shifting 55 said cam shaft lengthwise to bring the fashioning cams into action, knitting mechanism including yarn carrier mechanism, a slur cock carrier, driving means for said slur cock and carrier mechanism including gearing, a clutch between the cam shaft and gearing, said clutch being released by the shogging of the cam shaft when bringing the fashioning cams into action, a rocker shaft with means controlled thereby for setting the needle bar in position for knitting the reinforcements, a taper cam and means operated thereby for controlling the rocker shaft, 70 and means for operating said taper cam from said 75 gearing in order that when fashioning is being done said taper cam will be out of service.
65. In a full fashioned knitting machine, a needle bar, rocker mechanism for said needle bar for adjusting said bar while making tapered reinforcement, a tapered cam, a lever operated by said tapered cam for operating said rocker mechanism, means for shifting said lever along said tapered cam and means for stopping the rotation of said tapered cam while narrowing is being 80 done, substantially as described.
66. In a full fashioned knitting machine, needle bar, rocker mechanism for adjusting said needle bar while making tapered reinforcements, a taper cam composed of tapered sections in pairs, all of 85 which sections are adjustable, each pair of sections having its members spaced apart, one pair of sections being effective during the stroke of the machine in one direction and the other pair of sections being effective during the stroke of the machine in the other direction and a lever to be operated by the taper cam for rocking the needle bar, substantially as described.
67. A full fashioned knitting machine having 90 a plurality of substantially endless yarn guide carriers arranged one within the circuit of another, means for reciprocating said carriers and means for selecting the carriers in prescribed order to be driven by said reciprocating means.
68. A full fashioned knitting machine having 95 a plurality of yarn guide carriers, each arranged in an endless circuit, means for reciprocating said carriers and means for selecting the carriers in prescribed order to be driven by said reciprocating means, said carriers being arranged one 100 within the circuit of another and each consisting of a thin band set up vertically on edge.
69. Apparatus according to claim 32 in which the cam shaft is operated by a pawl and ratchet, said pawl having a two step forward movement 105 with an interval between the steps, a cam on the main cam shaft having two rises, one higher than the other for giving said pawl its two step movement during each revolution of said main shaft, a shield for rendering the pawl inactive on the ratchet and means for automatically setting 110 said shield in active or inactive position, substantially as described.
70. In combination in a knitting machine, a needle row, yarn guide means, and a flexible band 115 operating the yarn guide means, said band consisting of a flat strip set with its side face substantially parallel with the plane in which the needles lie and wholly carrying the said yarn guide means, substantially as described.
71. In combination in a knitting machine, a 120 row of needles, yarn guide means, a flexible endless band for operating the yarn guide means, said band being of substantially flat form presenting oppositely directed edges, and driving means for the band exerting its force upon the band edgewise thereof, substantially as described.
72. In combination in a full fashioned knitting machine, transfer points, a screw shaft for adjusting said transfer points, a pivotally mounted 125 fashioning frame in which the screw shaft is mounted, means for swinging said frame upwardly and downwardly, a drum mounted on the narrowing frame and having connection with the screw shaft for operating it, a band connected 130 with the drum, a guide for said band substantially in line with the pivotal axis of the fashioning frame and means for operating the band, substantially as described.
73. In combination in a full fashioned knitting 135 machine, transfer points, a screw shaft for adjusting said transfer points, a pivotally mounted fashioning frame in which the screw shaft is mounted, means for swinging said frame upwardly and downwardly, a drum mounted on the narrowing frame and having connection with the screw shaft for operating it, a band connected 140 with the drum, a guide for said band substantially in line with the pivotal axis of the fashioning frame and means for operating the band, substantially as described.
74. In combination in a full fashioned knitting 145 machine, transfer points, a screw shaft for adjusting said transfer points, a pivotally mounted fashioning frame in which the screw shaft is mounted, means for swinging said frame upwardly and downwardly, a drum mounted on the narrowing frame and having connection with the screw shaft for operating it, a band connected with the drum, a guide for said band substantially in line with the pivotal axis of the fashioning frame and means for operating the band, substantially as described.

- machine, a row of needles, a plurality of yarn guides, means for reciprocating said yarn guides along the needle row having substantially parallel front and rear portions connected at their end 5 portions whereby when one parallel portion moves in one direction the other portion moves in the opposite direction, a reciprocating driver having means to pick up and release said parallel rear portions of the yarn guide reciprocating means, 10 stops to arrest said rear parallel portions, a pair of screw threaded shaft portions coaxially mounted on the main frame, parallel with said yarn guide reciprocating means, for adjusting the stops and positioned opposite the said yarn guide reciprocating means and within the lengthwise limits thereof, narrowing points, carriers therefor, a pivotally mounted narrowing frame, a screw shaft mounted in the narrowing frame and on which said narrowing point carriers are mounted, and 15 means for operating the screw shaft of the point carriers and the screw shafts of the stops, substantially as described. 20
74. In combination in a full fashioned knitting machine, a main frame, narrowing points, a block carrying said points, a pivotally mounted fashioning frame, a screw shaft mounted in the narrowing frame for adjusting the narrowing point carrying block along the needle row, retrograde means for giving a backward movement to the 25 screw shaft mounted partly on the main frame and partly on the fashioning frame, said means normally being in inoperative condition and means operated by contact from the narrowing point carrier when the heel tab is to be formed for 30 rendering said retrograde means operative for the backward turning of the screw shaft. 35
75. A full fashioned knitting machine having a needle row, a plurality of yarn guides to deliver yarn to the needles, flexible endless members 40 wholly supporting and carrying said yarn guides and means for reciprocating said members with varying lengths of strokes. 45
76. In a full fashioned knitting machine and in combination, a needle row, means for moving yarns along said row, comprising endless flexible members having stretches arranged adjacent the needle row, and other stretches more remote from the needle row, and means cooperating with the more remote stretches for selectively driving 50 said members and for stopping the same variably. 55
77. In a full fashioned knitting machine having a plurality of yarn guides, substantially endless flexible members for moving said guides along the needle row, said members having stretches comparatively close together adjacent the needle row, and more remote stretches comparatively widely separated, and driving means for reciprocating said members engaging the said more remote and widely separated stretches 60 thereof. 65
78. A full fashioned knitting machine according to claim 77 in which stop means limit the movement of the endless flexible member in either direction, said stop means cooperating with the more remote stretches of the said members. 70
79. In a full fashioned knitting machine, a row of needles, an endless flexible member having one stretch parallel with the needle row, yarn guide means moved by said stretch along the needle row, means for reciprocating the endless flexible member, and stop means for arresting the endless flexible member, said member having a 75 stretch opposite to the first mentioned stretch with which opposite stretch the said stop means engages, substantially as described. 80
80. In a knitting machine a row of needles, yarn guides, a plurality of endless members for moving the yarn guides along the needle row, said endless members having stretches close together at and parallel with the needle row and having their opposite stretches more widely separated, means for selectively driving and stopping said endless members associated with said opposite stretches and means for guiding those portions of the members intermediate their widely separated stretches and the closely set stretches for directing the said intermediate portions along curved paths, and convergently from the widely separated stretches to the closely set stretches, substantially as described. 85
81. In combination in a full fashioned knitting machine, a row of needles, an endless flexible yarn carrier member having one stretch adjacent the needle row and another stretch more remote therefrom, a driver for said endless flexible member cooperating with said more remote stretch thereof, a screw shaft arranged with its axis parallel with the needle row, means for giving said screw shaft a rotary reciprocating movement, a driver for the endless member, a slur cock support reciprocated by the rotary reciprocating screw shaft, a flexible member connected to and reciprocated by the said slur cock support, 90 said flexible member being connected to the said driver to reciprocate the same. 95
82. In a knitting machine, and in combination, endless flexible means, yarn guide means traversed thereby along the needle row, guide means for directing the endless flexible means along its prescribed path, and reciprocating driving means engaging the endless flexible means for reciprocating the same, said endless flexible means having one stretch parallel with the needle 100 row and an opposite stretch engaged by said driving means, said driving means having a pawl 105 to frictionally engage a part on the flexible endless means and to automatically release therefrom when the said endless means is arrested, 110 automatically adjustable stop means for the said endless means to arrest it after it has performed the lengths of stroke according to the adjustment of the stop means, and means for automatically restoring the pawl to operative position to pick up the band on its return stroke, 115 substantially as described. 120
83. In combination in a knitting machine, a row of needles, yarn guide means, a flexible endless band having oppositely directed edges for operating the yarn guide means along the needle row, driving means arranged adjacent one edge of the band and exerting its force upon the band edgewise thereof, and stop means for the band adjacent the other edge of the band and exerting its 125 force edgewise of the band, substantially as described. 130
84. A fashioning knitting machine of the flat type comprising a straight row of needles, a yarn guide, an endless flexible member having a 135 stretch adjacent the needle row for moving the yarn guide back and forth along said needle row, and means for making said member perform different lengths of strokes, said means acting upon the opposite stretch of said endless member. 140
85. A fashioning knitting machine comprising a yarn guide, a flexible endless member having one stretch reciprocating adjacent and lengthwise of the needle row and constituting the sole 145 150

- means for supporting and carrying said yarn guide, and means for operating the endless member.
86. A fashioning knitting machine comprising a yarn guide, an endless flexible band moving said yarn guide back and forth along the needle row with different lengths of strokes, said band consisting of a flat strip, a dog on said flat strip connecting the ends of the flat strip, and drive and stop means acting upon said dog. 80
87. A fashioning knitting machine comprising a straight row of substantially vertically disposed needles, a flexible endless band set up vertically on edge having its front stretch extending along the needle row and its rear stretch extending substantially parallel with the front stretch, and a linearly reciprocating driver and stop means cooperating with the rear stretch of said band. 85
88. A fashioning knitting machine comprising a straight row of needles, a yarn guide, an endless flexible member having a stretch parallel with the needle row for moving the yarn guide back and forth along the needle row, linearly reciprocating driving means having a pawl for engaging the remote stretch of said endless member for reciprocating the same, restoring means mounted on the driving means to set the pawl in position to pick up and move the remote stretch of the endless member on the stroke in either direction, and means at the ends of the driver stroke mounted on the frame for operating said pawl restoring means first in one direction and then the other, substantially as described. 90
89. A fashioning knitting machine according to claim 88 in which the endless member carries a dog with which the pawl frictionally engages and from which engagement the pawl automatically releases itself when the member is arrested, and automatically adjustable stop means for arresting the member for varying the lengths of strokes of the band. 95
90. A fashioning knitting machine comprising a straight row of needles, a yarn guide, a flexible endless band for moving the yarn guide back and forth along the needle row, said band consisting of a flat strip, a dog mounted on the band and drive means and stop means for the band acting upon the dog, substantially as described. 100
91. A fashioning knitting machine comprising a straight row of needles, a yarn guide, an endless flexible band for moving the yarn guide along the needle row, a dog on the band, a reciprocating driver for the band having a passageway for the band and dog, a pawl on the driver movable to and from said passage to engage and disengage said dog, said dog when the pawl is in driving engagement therewith being housed in said passageway to be sustained against deflection by the walls thereof, substantially as described. 105
92. A fashioning knitting machine according to claim 91 in which the endless flexible band is in the form of a thin flat strip. 110
93. A fashioning knitting machine comprising a straight row of needles, a flexible endless member for moving a yarn guide back and forth along the needle row, drive means and stop means for the endless member acting upon the said member at substantially the same point in its circuit. 115
94. A full fashioning knitting machine comprising a straight row of needles, a yarn guide, an endless flexible member for moving the yarn guide along the needle row, which yarn guide partakes of the full length strokes of the member, automatically releasable and engageable drive means cooperating with that stretch of the endless member which is the more remote from and parallel with the needle row and stop means engaging the said remote stretch of the endless member. 120
95. A fashioning knitting machine comprising a straight row of needles, a yarn guide, an endless member connected with the yarn guide and having one stretch adjacent the needle row for moving said guide back and forth along the needle row, linearly reciprocating driving means for engaging the remote stretch of the endless member, automatically adjustable stop means for arresting the endless member, said driving means automatically releasing the endless member when arrested on either stroke, and means at the ends of the strokes of the driving means for setting said driving means to pick up the endless member on its return stroke in either direction, substantially as described. 125
96. In a flat knitting machine, a needle row, yarn carrier means reciprocating along the needle row, said carrier means comprising a flexible flat band arranged with its side face parallel with the plane in which the needles lie and a yarn guide carried by said flat band and extending in a direction transversely thereof, substantially as described. 130
97. In combination in a full fashioned knitting machine, a straight row of needles, a plurality of endless members, each for moving a yarn guide individual thereto back and forth along the needle row, stop means arresting the said endless members variably automatically for fashioning the fabric, driving means for selecting and reciprocating said endless members in prescribed order, and automatic selector means for adjusting the driving means for making its selection automatically, substantially as described. 135
98. A full fashioned knitting machine according to claim 97 in which means are provided for automatically moving the stop means to operative or inoperative position. 140
99. A full fashioned knitting machine according to claim 97 in which the driving means and the stop means cooperate with the stretches of the endless members which are the more remote from the needles than those stretches which move the yarn guides along the needle row. 145
100. A full fashioned knitting machine according to claim 97 in which the endless members are arranged one within the circuit of another. 150
101. A full fashioned knitting machine comprising a needle row and a plurality of endless flexible bands, one for each yarn guide, consisting of thin flat strips arranged one within the circuit of another with their side faces parallel with each other, and means for reciprocating the bands, said means engaging those stretches of the band that are the more remote from the needles, substantially as described. 155
102. A full fashioned knitting machine, a row of needles, yarn guides, endless members for moving said guides along the needle row, a reciprocating driver having means for selecting and moving the members by engaging those stretches thereof that are the more remote from the needles, and selector means at the ends of the stroke of the driver having abutment portions against which the selecting means on the driver strike as the driver is approaching its limit of movement in either direction. 160
103. A full fashioned knitting machine comprising a main frame, yarn guide operating members of endless form, a driver for said endless flexible members having means thereon for se- 165

lecting the endless flexible members to be driven, stops for arresting the endless flexible members, selector means on the frame having abutment portions to be contacted by the selecting means 5 on the driver, a cam shaft and cams thereon for controlling the stops and for controlling the selector means.

104. A full fashioned knitting machine comprising a row of needles, yarn guides, a plurality 10 of endless bands in the form of flat strips arranged with their side faces parallel and with one band within the circuit of another, said bands at one stretch having each a yarn guide carried thereby to be moved along the needle row, said 15 stretches being arranged close together, the stretches of said bands which are more remote from the needle row being more widely separated, a driver reciprocating along the more widely separated and more remote stretches of the bands, 20 means on the driver for engaging and releasing the bands, stops cooperating with the more remote stretches of the bands for arresting the bands, means for automatically adjusting the stops to vary the length of strokes of the bands, 25 selector means at the ends of the strokes of the driver having abutment portions for operating band engaging means on the driver to determine which of the bands will be operated, means for throwing the stops into and out of operative position automatically, and means for operating the selector means automatically, substantially as described.

105. A full fashioned knitting machine comprising a row of needles, yarn guides, endless flexible bands for moving the yarn guides along the 30 needle row, a reciprocating driver member for the flexible bands, having a channel for each of the bands, devices carried by the driver member, one for each band for engaging and moving the 35 same, means for selecting said devices automatically to render them active in prescribed order for driving the band, said bands when engaged by said devices being sustained against deflection by the walls of said channels, stops for arresting 40 the band, means for operating the stops to operative and inoperative position automatically, said channels being open at the upper portions for permitting engagement of the stops with the 45 bands, substantially as described.

50 106. In combination in a full fashioned knitting machine, a plurality of yarn guides, reciprocating carriers therefor, a reciprocating drive member, a plurality of pawls on said carrier for engaging and disengaging the yarn guide carriers, means on the driver for setting the pawls 55 to engage their respective yarn guide carriers, selector means at both ends of the stroke of the driver having abutment portions to be contacted by the pawl setting means on the driver for operating the same for automatically changing the 60 yarn, means for operating the needle bar

throughout a prescribed cycle in the knitting operation, said means including cam operated connections, a detent for temporarily holding said connections with the needle bar, with the needles in non-pressing position, while the automatic yarn change is taking place, and a cam for controlling said detent, a cam shaft on which 80 said cam is mounted, and cams on said shaft for operating the said selector means, substantially as described.

107. In combination in a knitting machine, a straight row of needles, yarn guide means, endless flexible means for moving the yarn guide means along the needle row, a screw shaft having rotary motion first in one direction and then 90 in the other direction, and a connection between said screw shaft and the endless flexible yarn guide moving means for operating the same, said screw shaft having its axis parallel with the needle row, and located in a plane perpendicular to the plane in which the endless flexible means lies and substantially between opposite stretches of said endless flexible means, 95 substantially as described.

108. A full fashioned knitting machine according to claim 74 in which the retrograde means comprises a pawl mounted on the main frame and a ratchet mounted on the fashioning frame, and the means operated by the narrowing point carrier for rendering the said retrograde pawl 105 operative is mounted on the fashioning frame, and has relative sliding connection with the pawl.

109. A full fashioned knitting machine according to claim 74 in which the retrograde means 110 comprises a pawl mounted on the main frame and a ratchet mounted on the fashioning frame, and the means operated by the narrowing point carrier for rendering the said retrograde pawl operative comprises a rock shaft mounted on the 115 fashioning frame having relative slidtable connection with the said pawl.

110. A fashioning knitting machine comprising a straight row of needles, yarn guide means, means for operating the yarn guide means back and forth along the needle row, said operating 120 means being of endless form and flexible and having parallel portions connected by curved end portions, means for guiding the curved end portions and for adjusting a curved end portion to keep the parallel portions substantially taut, driving and stop means cooperating with that stretch of the endless yarn guide operating means which is more remote from the needle row than the stretch which operates the yarn guides along 130 the needle row, means for controlling the driving means to engage or disengage the endless flexible means, and means for automatically adjusting the stop means, substantially as described.

KENNETH HOWIE. 135
CHARLES C. KRIEBLE.
